DENTAL AMALGAMATOR

Farron L. Stevens, Detroit, Mich., assignor to
Martin S. D'Essen, New York, N.Y.

Application December 16, 1947, Serial No. 791,977

9 Claims. (Cl. 259—75)

1

This invention relates to dental amalgamators, and it is an object of this invention to produce an amalgamator attachment to be mounted on a dental engine and employ its power for rapidly and uniformly mixing amalgam ingredients.

Another object is to provide, for use with a dental engine, an amalgamator which is normally held in an inoperative position and which can be adjusted to a position wherein a driving relation is established with the dental engine parts.

Another object is to produce an amalgamator which is adapted to be attached to a dental engine and which, in its operative or inoperative position, does not, in any way, interfere with the use or operation of the dental engine.

A further object is to produce an amalgamator as an attachment adapted to be mounted on a dental engine in such position that no interference is had with the normal engine use and which, responsive to simple adjustment, may be positioned to be driven from the driving cord of the engine rapidly and effectively to mix the amalgam ingredients.

A still further object is to produce an amalgamator in which the capsule containing the amalgam is resiliently gripped between spring fingers on the end of a rockable arm.

A still further object is to produce an amalgamator, of the type described, having an eccentric driven from the driving cord of the dental engine and cooperating with an elongate slot in the rockable arm to effect vigorous rocking movement of the arm.

Another object is to produce an amalgamator attachment formed of relatively few parts readily assembled to form a compact unit adapted to effect the desired agitation in an efficient manner.

These and other objects and advantages of this invention will become apparent from the following description, and for purposes of illustration, but not of limitation, an embodiment is shown in the accompanying drawing, in which—

Figure 1 is a fragmentary perspective view of a dental engine mounting an amalgamator embodying the features of this invention, the amalgamator being mounted thereon in an inoperative position;

Figure 2 is a view similar to that of Fig. 1 showing the amalgamator in the operative position;

Figure 3 is an enlarged detail view partially in section of the capsule positioned on the end of the rocker arm;

2

Figure 4 is an elevational view with parts in section of the amalgamator detached from the dental engine;

Figure 5 is a detail view partially in section of the pulleys and their supporting bracket; and

Figure 6 is an enlarged elevational view of the spring adjusting arm and its associated parts.

Referring now to the drawing, 10 indicates a conventional dental engine which includes a frame structure comprised of pairs of spaced parallel arms 11 and 12 occasionally braced by cross members 13. The frame carries a dental tool holder 14 on one end which is connected to be driven by a driving cord 15 threaded over pulleys 16 and actuated for linear movement in either direction by a motor, such as a reversible motor (not shown). Generally the cord travels in a region intermediate the spaced-apart frame arms 11 and 12.

20 The amalgamator attachment embodying the features of this invention has a supporting frame 17, one end of which 18 cooperates with a separate clamping arm 19 to form a clamping unit by which the attachment is secured rigidly to the frame. The cooperating parts 18 and 19 are each formed with a pair of curvilinear sections 20 which are spaced apart a distance corresponding to the span between frame arms 11 and 12. Interconnecting the cooperating parts 18 and 19 is a bolt 21 which extends through registered openings intermediate the curvilinear sections. The bolt carries a knurled nut 22 by means of which the cooperating parts disposed on opposite sides of the frame arms are brought into firm gripping relation therewith to form a rigid mounting.

25 The other end of the support 17 is turned to form a U-shaped portion 23, the outer arm 24 of which carries a rocker arm 25 pivoted thereto, as at 26, for swinging movement substantially in the same plane as the frame arms. The outer end portion of the rocker arm 25 is slotted and turned to provide a pair of spaced-apart spring fingers 28 and 29 for gripping a capsule 30.

30 As shown in Fig. 3, the capsule is an elongate tubular housing formed of rigid material, such as plastic, metal, glass, ceramic, and the like. The capsule has an annular rib 27 intermediate its ends adapted to be disposed between the spring fingers when in the mounted relation, and it is threaded in the region of its open end threadably to receive a screw closure 31. When desired, one or more pellets or pestles 32, such as cylindrical marbles, metal pieces, and the like, may be inserted in the capsule with the amalgam ingredi-

ents to assist in the amalgamating or mixing action.

The capsule ingredients are agitated by imparting rapid oscillatory movements to the rocker arm 25. For this purpose, there is provided a driving connection between the cord 15 and the rocker arm including a pin 33 fixed eccentrically to the side wall of a pulley 34. The pin is slidably in a longitudinal slot 35 formed in the intermediate portion of the rocker arm 25, and as the pulley rotates, the pin, which constantly operates in the slot, causes the arm to oscillate. Although a single pulley may be used, the preferred embodiment employs a pair of pulleys 34 and 37 rotatably mounted on opposite ends of a supporting bracket 36 which, as illustrated in Fig. 5, is pivoted on the bolt 21. The bracket 36 is shaped to dispose the pulleys 34 and 37 in radial alignment with the driving cord 15, and in the inoperative position, each is spaced from the cord, as illustrated in Fig. 1. However, when the bracket is rotated in the direction to bring the pulleys into operative engagement with the driving cord, a driving relation is established causing the rotation of the pulleys and concomitantly, through the eccentric connection, rocking movement of the rocker arm 25. Although mere driving engagement is sufficient to effect the desired results, it is more effective to turn the bracket to a position, such as is illustrated in Fig. 2, wherein the driving cord is so firmly engaged from opposite sides by the pulleys that it is distorted to a limited extent causing the cord further to be tensioned while enabling more substantial engagement between the cord and the respective pulleys.

Adjustment of the bracket 36 to carry the pulleys into and out of engagement with the cord is effected by means of a spring arm 38 secured at one end to a flange 39 integral with the bracket 36. The arm is formed with a curvilinear portion 40 which resiliently engages the bight 41 of the U-shaped member 23, the arm and the bight being provided with serrations 42 and 42a respectively on the engaging surfaces more effectively to resist inadvertent movement of the bracket, such as to or from its operative position of adjustment, and a finger grip 43 on its end for facilitating adjusting movement.

To use the amalgamator, the capsule is loaded with the desired amalgam ingredients and pellets and then subsequently sealed with the closure 31. The capsule is snapped into position with the rib 26 between the spring fingers 28 and 29 and the bracket is adjusted to the operative position by displacing the spring arm 38 to the left until the desired driving relation is established between the driving cord and the pulleys. While the cord is moving linearly, rotational movement is imparted to the pulley 34, and through the cooperating eccentric pin and slot arrangement, oscillatory movement is imparted to the rocker arm. The capsule on the end of the rocker arm is rapidly reciprocated in the longitudinal direction to effect a rapid mixing action such as will produce a uniform amalgam in a matter of relatively few seconds. When amalgamation is completed, the pulleys may be disengaged simply by lifting the spring arm 38 to disengage the serrations and by displacing the arm in the direction to the right, thereby to disengage the pulleys from the cord, enabling removal of the capsule in which the amalgam is carried ready for use.

From the description, it will be evident that

the cardinal features of this invention reside in an amalgamator attachment adapted to be mounted on a conventional dental engine in such position that no interference is had with the normal operation of the dental engine whether the amalgamator attachment is in its operative or inoperative position of use. The amalgamator normally is held in the inoperative position but, responsive to simple adjustment, may be rendered operative without, in any way, interfering with the operation or use of the dental engine or movable parts. Particular advantage results from the fact that the power for driving the amalgamator attachment is taken from the driving cord and not from the motor itself, thereby to prolong the useful life of the engine and reduce vibrations and noises which otherwise might result. Importance is also directed to the means for transmitting linear movement of the driving cord to oscillatory movements of the rocker arm in such manner that a noiseless, effortless, and efficient mixing action is secured.

While one embodiment of the invention has been shown and described in detail, it will be understood that it is illustrative only and is not intended to be a definition of the scope of the invention, reference being had for this purpose to the appended claims.

What is claimed is:

1. A dental amalgamator for use with a dental engine having a frame and a driving cord, said amalgamator comprising a support adapted to be mounted on the frame, an arm pivotally connected to the support, means on the end of the arm to hold a capsule, a pair of freely rotatable pulleys mounted on the support for adjustment in a manner to engage a single driving cord from opposite directions even while it is operating to establish a driving relation therebetween conjointly in the direction toward and away from the driving cord, means for holding said wheels in the adjusted position, and means for transmitting rotational movement of one of said wheels to oscillatory movement of said arms.

2. A dental amalgamator for use with a dental engine having a frame and a driving cord, said amalgamator comprising a support adapted to be mounted on a frame, an arm pivotally connected to the support, means on the end of the arm to hold a capsule, a pair of rotatable pulleys arranged on opposite sides of the driving cord and adjustable conjointly toward and away from said driving cord to establish a driving relation as a cord is distorted from its normal path of movement upon engagement with the pulleys, means releasably holding said pulleys in the adjusted position, means for adjusting said pulleys in one direction or the other, and cooperating eccentric and slot means for transmitting rotational movement of one of said pulleys to oscillatory movement of said arm.

3. A dental amalgamator, as claimed in claim 2, in which the means on the end of the arm for holding the capsule comprises spaced-apart spring fingers.

4. A dental amalgamator, as claimed in claim 2, in which the cooperating eccentric and slot means comprises a pin eccentrically mounted on one of the pulleys and slidably engaging an elongate slot in the arm.

5. A dental amalgamator for use with a dental engine having a frame and a driving cord, said amalgamator comprising a support adapted to be mounted on the frame, an arm pivotally mounted on the support, means on the end of

the arm to hold a capsule, a pair of rotatable pulleys movably mounted on the support for bodily shifting movement toward and away from the cord and arranged on opposite sides of the driving cord and adjustable conjointly toward and away from said driving cord to render said pulleys operative and inoperative respectively, an arm operatively connected at one end to adjust said pulleys and tensionally engaging a stop, the engaging surfaces of said stop and arm being adapted to prevent inadvertent relative movement of said pulleys from their operative position of adjustment, and cooperative eccentric and slot means for transmitting rotational movement of one of said pulleys to oscillatory movement of said arm.

6. A dental amalgamator for use with a dental engine having a frame and a driving cord, said amalgamator comprising a support carried by the frame, an arm pivoted on the support and having gripping means at one end, a bracket movably mounted on the support, a pulley on the bracket and which upon movement of the bracket in one direction is carried into operative engagement with the driving cord, and cooperating eccentric and slot means for transmitting rotational movement of the pulley to oscillatory movement of the arm about its pivot.

7. A dental amalgamator for use with a dental engine having a frame and a driving cord, said amalgamator comprising a support carried by the frame, an arm pivoted on the support and having gripping means at one end, a bracket pivoted intermediate its ends on the support, pulleys carried by the ends of the bracket and which upon pivotal movement of the bracket in one direction

operatively engage spaced-apart portions of the same driving cord from opposite directions to establish a driving relation, and cooperating eccentric and slot means for transmitting rotational movement of the pulleys to oscillatory movement of the arm about its pivot.

8. A dental amalgamator for use with a dental engine having a frame and a driving cord, said amalgamator comprising a support rigid with the frame, an arm pivoted at one end on the support and having gripping means on the other, a bracket pivotally mounted on the support at a point aligned with the driving cord, rotatable pulleys carried by the ends of the bracket whereby they are disposed on opposite sides of the driving cord operatively to engage the cord at spaced-apart portions when the bracket is pivoted in one direction, and cooperating eccentric and slot means for transmitting rotational movement of a pulley to oscillatory movement of the arm.

9. A dental amalgamator, as claimed in claim 8, in which a resilient member connects with the bracket to enable its adjustment and to hold the bracket in the adjusted position.
